UNITED STATES PATENT

KJARTAU BLEKASTAD, OF SEATTLE, WASHINGTON.
TICKET-HOLDER.

Specification of Letters Patent. Patented Sept. 14, 1909.
Application filed May 15, 1908. Serial No. 433,048.

934,386.

To all whom it may concern:

Be it known that I, KJARTAU BLEKASTAD, a citizen of the United States, residing at Seattle, in the county of King and State of Washington, have invented new and useful improvements in Ticket-Holders, of which the following is a specification.

This invention relates to car ticket holders, and the object of the invention is to provide, 10 a receptacle of the character, which is extremely simple in construction, and which is provided with means whereby the tickets within the receptacle may be ejected singly. With these and other objects in view the invention resides in the novel construction and combination of parts hereinafter fully described and claimed.

In the accompanying drawings, Figure 1 is a perspective view of a car ticket holder constructed in accordance with the present invention. Fig. 2 is a top plan view of the same, the cover being shown opened and the tickets removed from the box. Fig. 3 is a longitudinal sectional view upon the line 3—3 of Fig. 1. Fig. 4 is a transverse sectional view upon the line 4—4 of Fig. 3.

In the accompanying drawings, Figure 1 is a perspective view of a car ticket holder constructed in accordance with the present invention. Fig. 2 is a top plan view of the same, the cover being shown opened and the tickets removed from the box. Fig. 3 is a longitudinal sectional view upon the line 3—3 of Fig. 1. Fig. 4 is a transverse sectional view upon the line 4—4 of Fig. 3.

Figure 1 designates the box portion of the receptacle having a bottom 2, sides 3, front 4 and back 5. The front 4 is of a lesser height than the sides and back of the device, the purpose of which will hereinafter appear. The sides 2 have their inner edges adjacent the front 4 turned to provide engaging lips 6 for the hinged top 7 of the receptacle. The rear wall 5 has top 7 of the extremity rounded to provide the hinge by which the top 7 is secured upon the front wall 4. On a line with the top 7 are provided the sides 2 are provided with the top of the longitudinally extending ribs 8. These ribs 8 are adapted to act as a stop for a false bottom 10, which being placed within the receptacle and being held against the flat spring 10, which normally bears against the bottom 10, which is adapted for the top 7.

Toothed member 14, adapted for engagement with the cards, and having a reduced upwardly projecting portion adapted to be engaged between the walls of a longitudinal cut away portion 15 provided by the top 7. The ejector 13 is provided with a serrated head 16, by which the ejector is operated. From the above description it will be noted that the device constructed in accordance with the present invention is extremely simple and that the card can be ejected at a time, but a single card engaged during the operation. It is to be noted that the fingers of the ejector are rounded toward the projected through the top 7 and the front wall 11 of the box, so that when a card is passed through the receptacle without danger of the card being grasped by the teeth.

Having thus fully described the receptacle as new is:

A car ticket holder comprising a rectangular metal receptacle having the side walls adjacent the projecting upper edges bent, the receptacle, a hinged and the receptacle, a hinged closure, the edges of the receptacle, said closure longitudinally extending the closure being having an end, a head of the closure substantially close to the bottom of the receptacle, the bottom of the receptacle provided with a substantially close to the bottom of the receptacle.
